(57) **CLAIM**

The ornamental design for a brush, as shown and described.

DESCRIPTION

FIG. 1 is a rear perspective view of the brush according to the invention.

FIG. 2 is a front perspective view of the brush.

FIG. 3 is a rear elevation view of the brush.

FIG. 4 is a left-side elevation view of the brush, the right side elevation view being a mirror image thereof.

FIG. 5 is a front elevation view of the brush.

FIG. 6 is a top plan view of the brush; and,

FIG. 7 is a bottom plan view of the brush.

The broken lines are for the purpose of illustrating the environment of the article only and form no part of the claimed design.
